22 Claims. (Cl. 112—252)

The present invention relates to book-stitching machines for producing continuously stitched book-pads and more particularly concerns that type of machine in which an idle or locking stitch 5 may be made after the final section of each stitched book.

In order to facilitate cutting the books apart, which operation was hitherto always performed by hand, and also to obtain a complete or locked 10 stitch on the outside section, as is commonly practised in the art, an idle stitch is made, in known manner, between two successively stitched books. When the severing operation was performed by hand, a batten, having a suitable cutting 15 groove provided therein, was inserted between the books and under the threads which latter were then severed manually whilst lying drawn out over the batten and across the cutting groove therein.

20 In another known process in which strips of backing material are secured to the stitched books, the batten above described is replaced by a looping mechanism which serves to position the backing strip as required so that the latter 25 may be severed by a further manual operation. The cutting apart of the books by these means is particularly troublesome, because there is a great risk of severing the wrong threads, thus spoiling the book.

30 The object of this invention is to provide a method and means for automatically guiding and severing the threads forming the connections between successively stitched books of a continuously stitched book-pad.

35 According to this invention apparatus is provided to carry into effect the method of automatically severing the threads, when the stitching of a book forming part of a continuously stitched book-pad is completed in a thread-40 stitching machine is completed, so that the upper length of thread is mechanically severed adjacent the idle stitch made subsequent to the stitching of the final book section.

45 Referring to the accompanying diagrammatic drawings which show two embodiments of the apparatus for carrying the invention into effect:

Fig. 1 is an elevational view partly in section of one form of the mechanism above described and shown forming part of a thread stitching machine;

50 Fig. 2 is a view at right angles to Fig. 1, showing the positioning of the thread relatively to the guiding member after the formation of the idle stitch.

55 Fig. 3 is an elevational view partly in section

of a modified form of the above described mechanism also shown forming part of a thread-stitching machine.

Fig. 4 is an elevational view at right angles to that shown in Fig. 3.

Fig. 5 is a detail of the mechanism shown in Figs. 3 and 4 with the thread guiding member in the retracted position.

Fig. 6 is a similar view to Fig. 5 showing the thread guiding member advanced to engage the 10 thread, and

Fig. 7 is a detail in plan view showing the movable guiding member engaging the thread and about to draw it in the direction of the cutting 15 blade.

Referring to Figs. 1 and 2, a guide bar or rail 10, extending transversely over the machine and associated with the stitching needles c and thread looping needles d, carries a series of brackets 12a in which are adjustably mounted thread-guide 20 holders 14a. Each of the latter members supports a horizontally positioned thread guiding member 14, provided at its outer extremity with a hook 14', and a vertical knife blade 21 having an inclined cutting edge. The guiding members 25 14 and knife blades 21 are readily adjustable by moving the holders 14a in the brackets 12a as required. The knife blades could, if necessary, be mounted on the sides of the thread guiding members 14.

30 The outer extremities of the latter members are positioned in the recesses 22' formed by the serrations 22 provided in the lower edge of the bar 10 which, as shown in Fig. 2, forms a combined thread guide and needle guide for the 35 stitching apparatus. An oscillatory sheet carrier 23 of known type (see U. S. Patent No. 2,027,105) places the sheets or signatures to be stitched, beneath the stitching needles. When each thread guiding member 14 is suitably adjusted for the 40 purpose above described, the extremity thereof carrying the hook 14' is positioned approximately in the inclined plane occupied by the stitching needles and the thread held by the latter.

45 The operation of this embodiment of the apparatus is as follows:

A book signature is fed in known manner to the sheet carrier 23 which, in turn, positions the signature beneath the stitching needles, whereupon the signature is stitched in the usual manner. The thread is thus applied to the signature in the form of a tight stitch and is fed continuously by the stitching needles in known manner during the stitching of the signatures. The cross threads of each inserted stitch lie within the book 55

section to which the stitch is applied and only the looped portions of the stitches remain exposed on the book backs. When the requisite number of signatures forming a complete book have been stitched and an idle or locking stitch is to be made, the sheet carrier travels forward in an idle movement, that is to say, without a signature carried thereon (Fig. 1). The stitching needle *c* and looping needle *d* thus form an idle stitch *i. e.* a stitch not inserted in a book section after the last stitched signature *S* (Fig. 2) has been stitched. The portion *a'* of the thread which leads from the last stitched signature to the idle stitch together with the portion *a* of the thread which is fed from the needle *c* to form the idle stitch is positioned below the thread guiding member *14* immediately after the idle stitch is formed while the chain loop of the idle stitch is held by the looping needle *d*.

20 When the idle stitch is completed, the needle *c* moves upwardly and the thread *a* carried thereby, slides over the bevelled point *14'* of the needle *14* and is drawn by the needle *c* against the oblique edge *22''* of the recess *22'* and thus above the member *14*, and completely clear of the hook *14'* (Fig. 2). During the next stitching operation (when the first signature of the next book is stitched) the needle *c* moves downwardly together with the thread *a* and the latter is looped over the member *14* closely behind the hook *14'*. The thread is thus held on the said thread guiding member *14* and during the stitching operations for the next books subsequently formed in the book-pad, the first formed book is progressed along in the direction of the arrow *A* (Fig. 1) and the thread *a* thus passed along the member *14* and finally drawn across the edge of the cutting blade *21*. The end thread connecting each two books is thus mechanically severed as the completely stitched books are fed from the stitching needles.

25 In a second embodiment of the invention, the thread selector needle is reciprocated, in order to engage and guide the end thread, in a positively timed manner controlled by automatic means. For this purpose and according to this modified form of the apparatus shown in Figs. 3 and 4 the guide bar or rail *10*, extending transversely over the machine, carries a series of conveniently adjustable guide supports *12* in which slide members *13* are slidably mounted. The latter members each carry a thread guiding member *14* provided at its extremity with a hook *14'*. The slides *13* are adapted to be reciprocated in a substantially horizontal direction by means of the actuating mechanism shown in the drawings. An eccentric strap *15*, actuated from a drive shaft (not shown), carries a cam member *16* which engages a follower roller *18* mounted at the lower end of a pivotal lever *17*. The latter member is rigidly mounted on a horizontal rocking shaft *19* and resiliently held in engagement with the cam *16* by means of a spring *16a*. A downwardly extended arm *20*, also rigidly mounted on the rocking shaft *19* is in driving connection with the slides *13* and so reciprocates the latter according to the throw of the cam *16*. The latter, which is a single throw cam, performs one complete revolution for each section stitched or stitching operation of the machine.

30 As in the first described embodiment a vertical knife blade *21* is mounted on each slide *13* or thread guiding member *14* (Figs. 3, 4 and 5). The members *14* are positioned in recesses *22'* formed by the serrations *22* (Fig. 2) provided in the lower

edge of the bar *10* which, as shown in Fig. 4 is adapted to form a combined thread guide and needle guide.

The oscillating sheet carrier *23* which places the sheet, about to be stitched, beneath the stitcher head, is provided with a recess *11* in the side of the carrier uppermost, when the latter is in the operative position. Immediately above the recess is a downwardly extending finger *25* rigidly attached to a pivotal shaft *24* which latter is mounted on the bar *10*. An upwardly extending finger *26* is also rigidly mounted on the shaft *24*. The finger *26* has a V shaped notch provided at its upper end and adapted to engage a knife-edged member *28* carried at one end of a lever *29*, which is rigidly mounted on the rocking shaft *19*.

The operation of the apparatus in this embodiment of the invention is as follows:

A book section is fed to the sheet carrier *23* which, in turn, conveys the sheet towards the stitching means. The sheet, which covers the recess *11*, prevents the finger *25* from entering into the recess during the forward travel of the sheet carrier. The finger *25* is thus engaged and carried forward by the sheet and the shaft *24* rocked to position the finger *26* as shown in Fig. 6. That is to say, the V notch provided in the end of the finger *26* is positioned to receive the knife-edge member *28* and thus lock the shaft *19* against rotation. By these locking means the lever *17* and cam follower *18* are prevented from following the throw of the cam *16* and the thread guiding member *14* remains in the forward position (Figs. 3 and 6). Since the transverse threads of the stitches inserted into the book sections are inside the latter (Fig. 7) the forwardly advanced thread guiding member cannot engage therewith.

If, however, the complete number of sections for a book have now been stitched and an idle stitch is to be made, the sheet carrier again travels forward towards the stitching needles but without a book section carried thereon, that is to say, with the recess *11* uncovered. The fingers *25* and *26* carried by the pivotal shaft *24* have, meanwhile, assumed the position shown in Fig. 5. Owing to the recess *11* being uncovered the finger *25* is now able to enter into the recess during the advance of the sheet carrier *23* and the finger *26* thus remains in the same position, that is, clear of the knife edge member *28*. The lever *29*, now free to move, allows the lever *17* and cam follower *18* to follow the throw of the cam *16* so that the shaft *19* and lever *20* are rocked to reciprocate the thread guiding member or members.

The member *14* is thus retracted prior to the formation of the idle stitch and then again advanced upon the completion of the latter. The transverse threads of the idle stitch are of course free as shown in Figs. 2 and 7, the chain loop of the stitch being held by the hooked looping needle *d* while the free end *a* of the thread leads up to the needle *c*. As described in reference to the first embodiment the thread portion *a* of the idle stitch thus leading to the needle *c* is pulled upwardly against the oblique edge *22'* of the recess *22* formed in the needle guide *10* and thus parted from the lower thread *a'* leading from the last stitched book to the idle stitch. In this manner the threads are parted so that the hook *14'* is inserted between the superimposed threads forming the idle stitch and engages a part of the thread intermediate the ends leading to the

stitcher-needle eye and the last stitched book section respectively. Thus, the upper portion *a* of the thread is engaged behind the hook *14'* and is thereby prevented from slipping from the 5 thread guiding member. During the formation of the next inserted stitch the cam *16* is revolved and the member *14* together with the thread held thereon is retracted. As will be seen from Fig. 7, the thread held taut by the retracted guide is 10 positioned transversely of the knife blade *21*.

As above described the complete book is then pushed or conveyed onward towards the cutter blade *21* during the stitching of the following books of the book-pad. The end thread is thus 15 brought into contact with the cutting edge of the blade and being held taut, as described, is severed by the latter.

It will be appreciated that, by this arrangement, the thread to be severed cannot slip away 20 from the thread guide during the travel of the former to the severing blade. The thread guide, after drawing the thread onwards in the direction of the cutting blade, is again advanced by the cam actuated mechanism to the position shown in 25 Figs. 2 and 6 subsequently to engage the idle-stitch threads of the next completed book and the first engaged thread is thus prevented from tripping over the hook *14'* and so disengaging itself when slackened by the advancing book-pad.

The books which have been stitched, without the use of a backing strip, and severed by the 30 above method, can then be removed singly or in groups as desired. If, however, a backing strip has been used in securing the assembled book together, this must be severed independently. The last mentioned operation may be performed 35 manually and when performed in conjunction with the above described thread severing method, it does not entail any risk of spoiling the book by the severance of the wrong thread.

It will be clear from the foregoing description, that, since the thread severing blade and thread selector needle do not alter their position relatively to each other, these members may be 40 formed as a single unit which would be adjustably mounted on the rail *10* in a similar manner to the members *12a*.

We claim:

1. Apparatus for use in a thread stitching machine, which comprises in combination, thread stitching needles, a sheet carrier, a needle-guide bar having slots forming thread-guides, at least one thread-guiding member positioned in the thread guides, a thread severing member associated with each thread-guiding member, and means for engaging a thread portion with the said thread severing member.

2. Apparatus for use in a thread-stitching machine, which comprises in combination, thread stitching needles, a sheet carrier, a needle guide bar having slots forming thread guides and oblique recesses leading to the needle guides, at least one thread guiding member adjustably mounted adjacent the guide bar and positioned 65 in an appropriate thread guide slot, a thread severing member associated with each thread-guiding member, and means for engaging a thread portion with the appropriate thread-severing member.

3. In a book-stitching machine having thread sewing needles, a slotted needle guide bar, a supporting bracket attached to said guide bar, a stationary thread guiding member mounted on said supporting bracket and extending to a slot 75 in the said needle guide bar, a thread severing

member mounted upon the said thread guiding member, and means for retaining upon the said thread guiding member a thread engaged thereby.

4. A book-stitching machine comprising in combination thread stitching needles, a sheet carrier, a needle guide bar having slots forming thread guides, a supporting bracket attached to said needle guide bar, at least one reciprocatory thread guiding member mounted in the said supporting bracket and extending towards the thread 10 stitching needles, a severing blade mounted on said thread guiding member, means for moving the said thread guiding member in and out of the path of the thread extending from one of said stitching needles, and means for controlling 15 mechanically the movement of the said thread guiding member.

5. A book-stitching machine comprising in combination thread stitching needles, a sheet carrier, a needle guide bar having slots forming 20 thread guides, a supporting bracket attached to said needle guide bar, at least one reciprocatory thread guiding member mounted in the said supporting bracket and extending towards the thread stitching needles, a severing blade mounted on 25 said thread guiding member, means for moving the said thread guiding member in and out of the path of the thread extending from one of said stitching needles, and means for utilizing an idle stitch operation of the machine for controlling 30 the movement of the said thread guiding member.

6. In a book-stitching machine, means including thread-sewing needles and a movable sheet carrier for stitching book signatures in the form 35 of a continuously stitched book-pad, a thread-severing device, a thread-guiding member, means for moving said guiding member to intercept a thread forming part of a formed stitch so that the intercepted thread is guided into contact with 40 said severing device, and means actuated by said sheet carrier to control the movement of the said thread-guiding member.

7. The method of producing mechanically a continuously assembled and stitched multi-book- 45 pad with the interconnecting threads severed between the adjacent books thereof, which includes presenting the book signatures in succession to the stitching needles, progressing the stitched signatures away from said needles in the form 50 of a pad, positioning a thread-severing device adjacent the path of the stitching needles, and engaging with said device a selected thread interconnecting adjacent books of said pad.

8. The method of producing mechanically a 55 continuously assembled and stitched multi-book-pad with the interconnecting threads severed between the adjacent books thereof, which includes presenting the book signatures in succession to the stitching needles, progressing the stitched 60 signatures away from said needles in the form of a pad, positioning a thread-severing device adjacent the path of the book-pad, and guiding into contact with said device a selected thread interconnecting adjacent books of said pad. 65

9. The method of producing mechanically a continuously assembled and stitched multi-book- 70 pad with the interconnecting threads severed between the adjacent books thereof, which includes presenting the book signatures in succession to stitching needles, stitching each signature to attach it face-to-face against a previously stitched signature, progressing the stitched signatures facewise away from said needles in the form of a book-pad, positioning a thread guide, in the 75

- path of the thread leading from a formed stitch so that said thread becomes looped over said thread guide in the formation of the following stitch, and encountering said looped thread with a thread-severing device associated with said guide.
10. The method of producing mechanically a continuously assembled and stitched multi-book-pad with the interconnecting threads severed between the adjacent books thereof, which includes presenting the book signatures in succession to the stitching needles, progressing the stitched signatures away from said needles in the form of a pad, interposing a thread guide in the operative plane of the stitching needles so that a thread leading from a formed stitch becomes looped over said guide, and encountering said looped thread with a thread-severing device associated with said thread guide during the further stitching of the book-pad.
15. The method of producing mechanically a continuously assembled and stitched multi-book-pad with the interconnecting threads severed between the adjacent books thereof, which includes presenting the book signatures in succession to the stitching needles, progressing the stitched signatures away from said needles in the form of a pad, reciprocating a thread-engaging member through the operative plane of said thread-stitching needles so that a selected thread extending from a formed stitch to one of said needles is engaged by said member and severed in the subsequent stitching of the book-pad.
20. The method of producing mechanically a continuously assembled and stitched multi-book-pad with the interconnecting threads severed between the adjacent books thereof, which includes presenting the book signatures in succession to the stitching needles, progressing the stitched signatures away from said needles in the form of a book-pad, positioning a thread guide in the path of the thread leading from a formed stitch so that said thread becomes looped over said thread guide in the formation of the following stitch, and advancing the guided thread along said guide in the subsequent movement of the book-pad to bring it into engagement with a severing device.
25. The method of producing mechanically a continuously assembled and stitched multi-book-pad with the interconnecting threads severed between the adjacent books thereof, which includes presenting the book signatures in succession to the stitching needles, stitching each signature to attach it face-to-face against a previously stitched signature, progressing the stitched signatures facewise away from said needles in the form of a book-pad, positioning a thread guide in the path of the thread leading from a formed stitch so that said thread becomes looped over said thread guide in the formation of the following stitch, and advancing the guided thread along said guide in the subsequent movement of the book-pad to bring it into engagement with a severing element.
30. The method of automatically severing in a book-stitching machine the threads interconnecting the books of a continuously stitched book-pad, comprising stitching signatures together to form book-pads forming an idle stitch between adjacent book-pads, leading the thread from the idle stitch as said stitch is being completed over a thread guide, and subsequently cutting the thread positioned on the thread guide.
35. The method of automatically severing in a book-stitching machine the threads interconnecting the books of a continuously stitched book-pad, comprising stitching signatures together to form book-pads forming an idle stitch between adjacent book-pads, leading the thread from the idle stitch as said stitch is being completed over a thread guide, and subsequently moving the thread on the thread guide into engagement with a severing element.
40. The method of automatically severing in a book-stitching machine the threads interconnecting the books of a continuously stitched book-pad, comprising stitching signatures together to form book-pads forming an idle stitch between adjacent book-pads, leading the thread from the idle stitch as said stitch is being completed over a thread guide, and subsequently cutting the thread positioned on the thread guide.
45. The method of automatically severing in a book-stitching machine the threads interconnecting the books of a continuously stitched book-pad, comprising stitching signatures together to form book-pads forming an idle stitch between adjacent book-pads, leading the thread from the idle stitch as said stitch is being completed over a thread guide, and subsequently moving the thread on the thread guide into engagement with a severing element.
50. The method of automatically severing in a book-stitching machine the threads interconnecting the books of a continuously stitched book-pad, comprising stitching signatures together to form book-pads forming an idle stitch between adjacent book-pads, leading the thread from the idle stitch as said stitch is being completed over a thread guide, and subsequently moving the thread on the thread guide into engagement with a severing element.
55. The method of automatically severing in a book-stitching machine the threads interconnecting the books of a continuously stitched book-pad, comprising stitching signatures together to form book-pads forming an idle stitch between adjacent book-pads, leading the thread from the idle stitch as said stitch is being completed over a thread guide, and subsequently moving the thread on the thread guide into engagement with a severing element.
60. In a machine for continuously stitching book-pads, a thread-carrying needle, a looping needle, a signature carrier for positioning signatures beneath said needles, a thread guide positioned between said needles adjacent the thread-carrying needle and out of the path of movement of the thread when a signature is stitched, means operable upon the failure to position a signature beneath said needles and the formation of an idle stitch for guiding the thread from said idle stitch onto said thread guide, and severing means positioned to sever the thread on said thread guide.
65. In a machine for continuously stitching book-pads, a thread-carrying needle, a looping needle, a signature carrier for positioning signatures beneath said needles, a thread guide po-
70. In a machine for continuously stitching book-pads, a thread-carrying needle, a looping needle, a signature carrier for positioning signatures beneath said needles, a thread guide po-
75. In a machine for continuously stitching book-pads, a thread-carrying needle, a looping needle, a signature carrier for positioning signatures beneath said needles, a thread guide po-

- sitioned between said needles adjacent the thread-carrying needle, said guide being positioned out of the path of movement of the thread when signatures are being stitched and in the 5 path of travel of the thread leading from an idle stitch resulting from the failure to position a signature beneath the needles so that upon the formation of an idle stitch the thread will be engaged with said guide, and means for severing 10 the thread on said guide.
21. A machine for producing mechanically a continuously stitched multi-book-pad with the interconnecting threads severed between the adjacent books thereof, which includes at least one 15 thread-carrying needle, at least one thread-looping needle, a signature carrier arranged to present the signatures one by one to said needles which pass at least one continuous thread through each signature in turn to bind said signatures together in the form of a continuous 20 book-pad, a thread guide positioned adjacent the thread-carrying needle, means operable as certain stitches are formed to loop the thread forming the stitch over said guide, and a thread-sev-

ering device associated with said guide to engage the portion of the thread looped over said guide upon the advancement of the book-pads towards the severing device.

22. A machine for producing mechanically a 5 continuously stitched multi-book-pad with the interconnecting threads severed between the adjacent books thereof, which includes at least one thread-carrying needle, at least one thread-looping needle, a signature carrier arranged to present the signatures one by one to said needles which pass at least one continuous thread through each signature in turn to bind said signatures together in the form of a continuous book-pad, means operable during the formation 10 of a stitch to shift said thread guide to cause a portion of the thread of the stitch being formed to loop over said guide, and a thread-severing device associated with said guide whereby, upon attachment of further signatures, said looped 15 thread will be advanced to the severing device.
